(57) CLAIM

We claim the ornamental design for the ear buds for headset, as shown and described.

DESCRIPTION

FIG. 1 depicts an isometric view of a first ear bud of earbuds for a headset showing our new design;

FIG. 2 depicts a front view of the first ear bud of FIG. 1.

FIG. 3 is a side view of the first ear bud of FIG. 1.

FIG. 4 is an opposite side view of the first ear bud of FIG. 1.

FIG. 5 is a back view of the first ear bud of FIG. 1.

FIG. 6 is a top view of the first ear bud of FIG. 1.

FIG. 7 is a bottom view of the first ear bud of FIG. 1.

FIG. 8 is an off-angle view of the first ear bud of FIG. 1.

FIG. 9 is another off-angle view of the first ear bud of FIG. 1.

FIG. 10 is an isometric view of a second ear bud of earbuds for a headset showing our new design;

FIG. 11 is a front view of the second ear bud of FIG. 10.

FIG. 12 is a side view of the second ear bud of FIG. 10.

FIG. 13 is an opposite side view of the second ear bud of FIG. 10.

FIG. 14 is a back view of the second ear bud of FIG. 10.

FIG. 15 is a top view of the second ear bud of FIG. 10.

FIG. 16 is a bottom view of the second ear bud of FIG. 10.

FIG. 17 is an off-angle view of the second ear bud of FIG. 10.

FIG. 18 is another off-angle view of the second ear bud of FIG. 10.

FIG. 19 depicts the isometric view of the first ear bud of FIG. 1 without shading but including tangent lines, which are shown as dashed or dotted lines.

FIG. 20 depicts the front view of the first ear bud of FIG. 2 without shading but including tangent lines, which are shown as dashed or dotted lines.

FIG. 21 depicts the side view of the first ear bud of FIG. 3 without shading but including tangent lines, which are shown as dashed or dotted lines.

FIG. 22 depicts the opposite side view of the first ear bud of FIG. 4 without shading but including tangent lines, which are shown as dashed or dotted lines.

FIG. 23 depicts the back view of the first ear bud of FIG. 5 without shading but including tangent lines, which are shown as dashed or dotted lines.

FIG. 24 depicts the top view of the first ear bud of FIG. 6 without shading but including tangent lines, which are shown as dashed or dotted lines.

FIG. 25 depicts the bottom view of the first ear bud of FIG. 7 without shading but including tangent lines, which are shown as dashed or dotted lines.

FIG. 26 depicts the off-angle view of the first ear bud of FIG. 8 without shading but including tangent lines, which are shown as dashed or dotted lines.

FIG. 27 depicts the other off-angle view of the first ear bud of FIG. 9 without shading but including tangent lines, which are shown as dashed or dotted lines.

FIG. 28 depicts the isometric view of the second ear bud of FIG. 10 without shading but including tangent lines, which are shown as dashed or dotted lines.

FIG. 29 depicts the front view of the second ear bud of FIG. 11 without shading but including tangent lines, which are shown as dashed or dotted lines.

FIG. 30 depicts the side view of the second ear bud of FIG. 12 without shading but including tangent lines, which are shown as dashed or dotted lines.

FIG. 31 depicts the opposite side view of the second ear bud of FIG. 13 without shading but including tangent lines, which are shown as dashed or dotted lines.

FIG. 32 depicts the back view of the second ear bud of FIG. 14 without shading but including tangent lines, which are shown as dashed or dotted lines.

FIG. 33 depicts the top view of the second ear bud of FIG. 15 without shading but including tangent lines, which are shown as dashed or dotted lines.

FIG. 34 depicts the bottom view of the second ear bud of FIG. 16 without shading but including tangent lines, which are shown as dashed or dotted lines.

FIG. 35 depicts the off-angle view of the second ear bud of FIG. 17 without shading but including tangent lines, which are shown as dashed or dotted lines; and,

FIG. 36 depicts the other off-angle view of the second ear bud of FIG. 18 without shading but including tangent lines, which are shown as dashed or dotted lines.

Each of the ear buds in the accompanying figures, i.e., a first ear bud and a second ear bud, may be a part of a headset that may be placed, i.e., worn, in a person's ears.

Line shading is used in the accompanying Figures to convey surface shading and contouring, and not texture, in FIGS. 1-18.

The broken lines shown in the FIGS. 1-18 illustrate portions of the ear bud that form no part of the claimed design; the dash-dot-dash boundary rectangle is used to indicate a transition from claimed subject matter to unclaimed subject matter. In FIGS. 19-36, the dash-dash broken lines illustrate wireframe lines that form not part of the claimed design.
